Primary Examiner — Karen S Acker*Assistant Examiner* — Jerry Shiuan-Hua Hsu(74) *Attorney, Agent, or Firm* — Sughrue Mion, PLLC(57) **CLAIM**

The ornamental design for a tow tractor, as shown and described.

DESCRIPTION

FIG. 1 is a front, top and right side perspective view of a tow tractor showing my new design;

FIG. 2 is a front view thereof;

FIG. 3 is a rear view thereof;

FIG. 4 is a top plan view thereof;

FIG. 5 is a right side view thereof;

FIG. 6 is a left side view thereof;

FIG. 7 is an enlarged view of the portion indicated by line 7-7 in FIG. 1; and,

FIG. 8 is an enlarged view of the portion indicated by line 8-8 in FIG. 4.

The bottom plan view is omitted since it is unornamented and forms no part of the claimed design. The broken lines illustrate portions of the tow tractor and form no part of the claimed design. The dash-dotted lines denote the boundary of the claim and form no part of the claimed design.
